S. H. HALE.

GAS MIXER.

APPLICATION FILED AUG. 5, 1914.

1,127,757.

Patented Feb. 9, 1915.

UNITED STATES PATENT OFFICE.

STEPHEN H. HALE, OF NEODESHA, KANSAS.

GAS-MIXER.

1,127,757.

Specification of Letters Patent.

Patented Feb. 9, 1915.

Application filed August 5, 1914. Serial No. 855,210.

To all whom it may concern:

Be it known that I, STEPHEN H. HALE, a citizen of the United States, residing at Neodesha, in the county of Wilson, State of Kansas, have invented certain new and useful Improvements in Gas-Mixers; and I do hereby declare the following to be a full, clear, and exact description of the invention, such as will enable others skilled in the art 10 to which it appertains to make and use the same.

This invention relates to an air and gas mixing device, and is in the nature of an improvement on my Patent #970,919, patented Sept. 20, 1910.

The device is particularly adapted for use in connection with the burning of natural gas, artificial gas and other gaseous materials, which are required to be mixed with 20 air in order to obtain the proper combustion and the greatest number of heat units as is the device in the afore-mentioned patent.

The object of the invention is to provide an improved device wherein there will be 25 two positive shut-offs, so that when the gas is shut off the possibility of the gas escaping will be practically obviated.

A further object of the invention is to so construct the device that the second shut-off will be opened in such manner that the 30 full pressure of gas will be behind the same at this time.

A still further object of the invention is to provide means on the main shut-off cock 35 which will seat the said cock properly, irrespective of the wear thereon.

With these and other objects in view, such as will appear as the description progresses, my invention comprises the combination and 40 arrangement of parts as set forth in and falling within the scope of the appended claims.

Referring to the drawing: Figure 1 is a side elevation of my device. Fig. 2 is a plan view of the device. Fig. 3 is a longitudinal sectional view, showing the cocks in their closed positions. Fig. 4 is a longitudinal sectional view taken on a vertical plane showing the cocks in their open positions. 50 Fig. 5 is a horizontal sectional view show-

ing the cocks in their open positions. Fig. 6 is a section on line 6—6 of Fig. 3.

Referring to the drawings by reference characters wherein like parts are indicated by like characters throughout the several views: the device comprises a valve casing 1 having a longitudinally extending tapered bore 2 and a transversely extending passage 3, the said passage 3 communicating with a chamber 4 in an outwardly extending nozzle 5. The said nozzle 5 extends into and is secured within a pipe 6 which has cutaway portions forming openings 7 and on the end of which is a collar 8 which is threaded so as to be attachable to a burner or the like. 65

Revolubly mounted in the tapered bore 2 in the casing 1 is a tapered valve plug 9 which has a transversely extending slot 10 therethrough, the said slot being adapted to be brought into registration with the transversely extending passage 3 in the casing so that gas may blow through the said passage and through the chamber 4 in the nozzle 5, and is so arranged that when the plug 9 is turned in the proper position the passing 70 of gas through the said passage 3 will be prevented. In the lower end of this plug 9 is detachably mounted a pin 11 which extends through a washer 12 on the lower end of the casing 1. A coil spring is located beneath and bears against the lower end of the casing 1 at one of its ends and at its other end against the head of the pin 11 so that the plug 9 is normally pulled downwardly and will therefore be seated tightly 75 within the casing 1, irrespective of the wear of the said plug. The plug is so operated that the slot 10 will be in alinement with the passage 3 in the casing 1, the gas passing through the said passage and through 80 the chamber 4 in the nozzle 5 and is projected from the end of the said nozzle and into the collar 8. As the gas passes the openings 7 the suction created thereby draws air through the said openings and thus effectually mingles the air with the gas.

A sleeve 13 is slidably mounted on the pipe 6 and encircles the same and this pipe is connected to the handle 14 of the plug 9 by means of a pivotally supported link 15, so 100

that when the plug 9 is turned to let gas into the nozzle 5 the sleeve 13 will be moved upon the pipe 6 to partially open the cut-away portion 7 so as to allow a proportionate amount of air to pass therethrough. As the passage 3 is gradually uncovered so the openings 7 will be gradually uncovered and as the flow of gas is increased so will the amount of air passing therethrough be 10 proportionately increased.

Extending longitudinally of the plug 9 and across the slot 10 is a pin 16 on which is pivotally mounted an outwardly extending rod 17 on the end of which is a valve head 18 adapted to seat on a valve seat 19 in the end of the nozzle 5. The valve 18 is so arranged that when the plug 9 in the casing 1 is in such position as to close the passage 3 the said valve 18 is in place in the valve seat 19 and thus the escape of gas through the nozzle 5 is doubly prevented.

The chamber 4 in the nozzle 5 is of considerably greater diameter than the rod 17 and thus the said rod may have pivotal 25 movement within the said chamber 4 about the valve 18 as the pivot.

When the plug 9 closes the passage 3 and the valve 18 is in place on its seat 19 and it is desired to allow gas to flow through the said nozzle, the handle 14 of the plug 9 is turned and during the initial movement of this plug 9 the pin 16 moves about an arc of a circle and the rod 17 rocks about the valve 18 as the pivot without transmitting 35 to the valve 18 any movement which would tend to unseat the same from its valve seat 19 and thus the passage 3 is uncovered previous to the uncovering of the end of the nozzle or the unseating of the valve 18 and 40 the gas therefore rushes into the nozzle 5 and maintains full pressure behind the said valve 18 before the valve is opened and when movement of the handle 14 is continued the valve 18 is removed from its seat 45 and the gas in the nozzle 5 is ejected from the end of the said nozzle under full pressure and consequently the gas passes the openings 7 under full pressure immediately upon the opening of the valve 18. This is especially 50 beneficial because of the fact that it allows the operator to get the highest degree of temperature obtainable from the gas as soon as the gas is ejected from the nozzle 5.

From the foregoing description it may 55 readily be seen that I have provided a gas mixer wherein the gas and air will be effectively mixed and the amount of air mixed with the gas will be proportionately increased or decreased as the amount of gas is 60 increased or decreased. I have constructed the device so that there are two valves, one in the pipe and one in the nozzle which will both be seated at the same time to prevent

the escape of gas. I have further so constructed the device that the stop cock or valve in the supply pipe will open slightly in advance of the opening of the valve in the nozzle so that the full pressure of gas will be behind the said valve in the aforementioned nozzle before the same is unseated 70 and thus upon the unseating of the same the gas will be ejected from the nozzle under full pressure.

While I have illustrated and described a particular embodiment of my invention, it is 75 merely for the sake of illustration and I do not wish to be limited to this particular embodiment as it is obvious that numerous changes may be made within the details of construction thereof without departing from 80 the spirit of the invention and without exceeding the scope of the claims.

What is claimed is:

1. In an air and gas mixing device, a 85 valve casing, a plug rotatably mounted in said casing, resilient means for retaining said plug in its seat, a nozzle connected to and extending from said casing, a pipe encircling said nozzle and having cutaway portions at the free end thereof, said plug 90 having a slot extending transversely therethrough, a rod pivotally secured to said plug adjacent the periphery thereof and extending longitudinally within the said nozzle, and a valve head on the end of said rod 95 arranged to close the said nozzle, the said plug and said valve head being so arranged with relation to each other that the valve head is unseated subsequently to the opening of the plug.

2. In an air and gas mixing device, a pipe having openings in the periphery thereof, a nozzle extended into and secured within the said pipe, a valve casing secured to the end of the said nozzle, a plug mounted in 105 said casing, a valve head slidably mounted within the said nozzle and adapted to close the end of the same, and a rod secured to the said head and pivotally connected to the said plug at the periphery thereof.

3. In an air and gas mixing device, a pipe having openings therein, means for partially covering the openings, a nozzle secured within the said pipe, a valve head slidably mounted in the said nozzle and adapted to 115 close the end of the same, a valve casing secured to the other end of the nozzle and having a tapered plug therein, and means connected to said valve head and said plug constructed and arranged so that the opening in the valve casing will be uncovered slightly previous to the unseating of the afore-mentioned valve head.

4. In an air and gas mixing device, a pipe having a plurality of peripherally arranged 125 openings therein, a nozzle mounted within

the said pipe and extending longitudinally thereof, a valve casing secured to one end of the said nozzle, a plug turnably mounted in said casing and having a slot extending transversely therethrough, a pin within the said plug adjacent the periphery thereof, a rod secured to said pin and extending longitudinally of the nozzle, a head on the end of said rod and adapted to close the end of

the nozzle, and means operatively connected 10 to the plug to partially cover the openings of the afore-mentioned pipe.

In testimony whereof, I affix my signature, in the presence of two witnesses:

STEPHEN H. HALE.
